SURFACE COOLER

Albert O. Flindt, Schenectady, N. Y., assignor to
 General Electric Company, Schenectady, N. Y.,
 a corporation of New York

Application December 1, 1936, Serial No. 113,633

8 Claims. (Cl. 257—239)

My invention relates to surface coolers, and more particularly to surface coolers such as used in electrical apparatus or dynamo-electric machines.

5 In surface coolers, the cooling medium is usually passed between suitable headers through a plurality of tubes supported by tube plates in the headers, and the medium to be cooled or condensed is passed over the outside of the tubes within an enclosing chamber. The medium after it has been cooled or condensed is then collected and employed as desired. In ships or other installations employing impure or salt water as a cooling medium, it is very important that the medium cooled or condensed in the surface cooler does not come into contact with the cooling medium, as the latter would contaminate the medium cooled or condensed. However, in actual practice this is a thing difficult to prevent as often 10 one or more of the joints between the tubes and the tube plates in the headers become loose and the cooling medium leaks into the enclosing chamber containing the medium to be cooled. Furthermore, the tubes themselves often 15 develop leaks or burst due to becoming corroded, pitted or cracked, for example, resulting in leaking of the cooling medium into the enclosing chamber containing the medium to be cooled.

Accordingly, an object of my invention is to 20 provide an improved surface cooler construction which will prevent contact between the cooling medium and the medium to be cooled.

Further objects and advantages of my invention will become apparent as the following description proceeds, and the features of novelty which characterize my invention will be pointed out with particularity in the claims annexed to and forming a part of this specification.

For a better understanding of my invention 25 reference may be had to the accompanying drawing, in which Fig. 1 is a side elevation of a surface cooler embodying my invention with the cover plate removed; Fig. 2 is an end elevation, partly in section, of the surface cooler shown in Fig. 1; Fig. 3 is an enlarged sectional view of a portion of the surface cooler of Fig. 1, showing the connection between a tube, a tube plate, and a conduit surrounding a tube; Fig. 4 is an enlarged sectional view of the tube and the surrounding conduit shown in Fig. 3; and Fig. 5 is a perspective view of the surrounding conduit shown in Figs. 3 and 4.

Referring to the drawing, in Fig. 1 I have 30 shown a surface cooler comprising two spaced apart headers 10 and 11 communicating with

each other through a plurality of similar tube constructions 12. The headers 10 and 11 are rigidly held in spaced relation by two substantially parallel spaced sheets 13 provided with flanged ends 13a secured thereto. The sheets 13 form opposed side walls of a chamber 14 which encloses the tube constructions 12, and are provided with flanged sides 15 which support suitable connections for passing a medium to be cooled through the chamber 14 in contact with 10 the tube constructions 12.

The header 10, as best shown in Fig. 2, includes a flanged end plate 16 and an upstanding partition 17 which forms two chambers 18 and 19 therein, communicating respectively with the 15 back rows and the front rows of the tube constructions 12. The end plate 16 is provided with two flanged couplings 20 and 21 communicating, respectively, with the chambers 18 and 19 in the header 10. The header 11 is provided with a 20 flanged end plate 22 having a chamber therein in open communication with all of tube constructions 12. The flanged couplings 20 and 21 are connected, respectively, to a source of supply of cooling water or other medium and an outlet 23 therefor. The cooling water, such as salt water, for example, enters the flanged coupling 20 in the direction of the arrow 23, passes into the chamber 18 of the header 10 and down through the back rows of the tube constructions 12 into the 30 header 11. The cooling water then passes from the header 11 through the front rows of the tube constructions 12 into the chamber 19 in the header 10, from which it is discharged through the flanged coupling 21 in the direction of the arrow 35 24 into an outlet. Thus the cooling water traverses the length of chamber 14 in both directions through the tube constructions 12, which permits the cooling water to absorb heat from the medium to be cooled which is passed through the 40 chamber 14 over the tube constructions 12.

Referring to Fig. 3 it will be seen that each of the tube constructions 12 includes a metallic heat exchange tube 30 communicating between the headers 10 and 11 and secured by expanding and 45 flaring the ends of the same in an opening 31a in a tube plate 31 provided each of the headers, and a metallic conduit 32 closely surrounding and tightly fitting the tube 30 in surface-to-surface or metal-to-metal contact therewith. Adjacent the tube plate 31 there is provided an auxiliary plate 33 having an opening 33a therein which is aligned axially with the opening 31a in the plate 31 to 50 allow the tube 30 to pass through the auxiliary plate. The end of the conduit 32 is secured by 55

expanding and flaring the same in the opening 33a in the auxiliary plate. The auxiliary plate 33 is spaced from the tube plate 31 a short distance to provide a space 34 therebetween.

5 One or more passages 35 are provided between the contacting surfaces of the tube 30 and the conduit 32 which communicate with the space 34 between the plates 31 and 33. These passages 35 between the contacting surfaces of the tube 10 30 and the conduit 32 are provided by forming a number of grooves in the exterior surface of the tube 30, by forming a number of grooves in the interior surface of the conduit 32, or by forming grooves in both of the surfaces. However, due to the fact that it is often desirable to replace one of the tubes 30 during service, I prefer that the tube 30 be of conventional construction having a smooth exterior surface. Accordingly, the interior surface of the conduit 32 is 15 provided with a plurality of grooves or flutes 35 in its interior surface extending throughout the length of the conduit. The exterior surface of the conduit 32 is provided with a suitable finned structure 36 secured thereto in good heat exchange relationship therewith. For example, the finned structure 36 may be secured to the conduit 32 in any suitable manner, as by welding, soldering, brazing or the like. Referring to Figs. 4 and 5, it will be observed that the interior surface of 20 the conduit 32 directly engages the exterior surface of the tube 30 entirely about its circumference, except for the widths of the grooves 35 formed in the interior surface of the conduit 32, at which points passages are formed between 25 the tube and the conduit extending throughout the lengths of these members. These passages formed by the grooves 35 serve to conduct any cooling water leaking from the tube 30 to the exterior of the surface cooler as heretofore explained. Heat absorbed in the chamber 14 by 30 the finned structure 36 readily passes through the conduit 32 to the tube 30 and into the cooling water passing therethrough, which carries the heat to the exterior of the surface cooler. Thus, 35 an improved heat exchange construction is provided which has substantially the same thermal conductivity as ordinary solid tube constructions and which also prevents damage due to leaking tubes. Furthermore, the conduit 32 closely surrounds the tube 30 reinforcing the latter and 40 reduces strains therein due to the pressure of the cooling water flowing therethrough.

A plurality of tube constructions 12 such as 45 described above extend between the headers 10 and 11 and are arranged in staggered relationship, as will be observed in Fig. 2, in order to provide a zig-zag path for the medium to be cooled which is passed through the chamber 14 over the tube constructions.

50 A communication is established between the space 34 and the exterior of the surface cooler by drilling an opening 37 in the plate 31 near the bottom of the space 34 and drilling another opening 38 in the plate 31 in intersecting relationship with the opening 37. A pipe 39 is threaded into the opening 38 to conduct any cooling water leaking into the space 34 to a drain. Suitable gaskets 40 and 41 are interposed, respectively, 55 between the end plate 16 and the tube plate 31 and between the tube plate 31 and the auxiliary plate 33 and the header assembly is securely fastened to the flanged ends of the sheets 13 to provide a rugged joint therebetween. A series of bolts 42 are passed through aligned openings provided in the flanged end 13a of the sheets 13, the

auxiliary plate 33, the gasket 41, the tube plate 31, the gasket 40 and bosses 44 formed on the end plate 16.

The header 11 is provided with a tube plate and an auxiliary plate constructed in a manner similar to that described in connection with the header 10, and is secured in a like manner to the flanged ends 13a of the sheets 13 to provide a unitary surface cooler construction.

In the surface cooler described above, if any cooling water should leak from the headers 10 and 11 due to faulty joints between the heat exchange tubes 30 and the tube plates 31, it will be collected in the spaces 34 at either end of the surface cooler and discharged through the pipes 39 to the exterior of the surface cooler. Likewise any cooling water leaking from a heat exchange tube 30 along its length due to a rupture or opening therein will be collected by its surrounding conduit 32 and conducted through the grooves 35 in the interior surface thereof to the spaces 34 at either end of the surface cooler from which the leaking cooling water will be discharged to the exterior of the surface cooler. Thus, it is apparent that no cooling water may gain entrance to the chamber 14 to be commingled with the medium to be cooled passing therethrough. My surface cooler is particularly adapted for use on ships or the like, which employ salt water from the ocean for cooling the various heat exchange devices employed aboard the ships. It is evident from the foregoing that I have provided a surface cooler construction which positively prevents contact between the cooling water circulated through the headers 30 and heat exchange tubes therein and the medium to be cooled which is passed over the heat exchange tubes.

While I have described my invention in connection with a surface cooler, it will be apparent that it is applicable to other heat exchange devices, and I do not desire my invention to be limited to the specific embodiment shown and described, and I intend in the appended claims to cover all modifications thereof which do not depart from the spirit and scope of my invention.

What I claim as new and desire to secure by Letters Patent of the United States is:

1. A surface cooler comprising a chamber, a heat exchange tube extending into said chamber, means for connecting said tube to a source of cooling liquid supply, and a leakage interceptor conduit extending along the length of said tube and closely surrounding said tube in surface-to-surface contact therewith, said tube and said conduit having a passage arranged therebetween communicating with the exterior of said chamber.

2. A surface cooler comprising a chamber, a heat exchange tube extending into said chamber, means for connecting said tube to a source of cooling liquid supply, and a leakage interceptor conduit extending along the length of said tube and closely surrounding said tube in heat exchange relationship therewith, said conduit having a flute formed on the interior surface thereof extending along its length and communicating with the exterior of said chamber.

3. In a heat exchanger, a pair of spaced headers, a series of tubes extending between said headers for liquid flow from one header to the other, a leakage interceptor tube embracing each liquid flow tube, said tubes having their adjacent surfaces closely fitted together throughout a portion of their extent for the ready trans-

fer of heat between and the mutual reinforcement of said tubes, with the remaining portion of the adjacent surfaces providing a passage between the tubes, air fins on the interceptor tubes, and a header independent of the first mentioned headers and common to the several passages for receiving the liquid leakage from the first mentioned tubes.

4. In a heat exchanger, a pair of spaced headers, fluid flow passages connecting the headers and each comprising an inner tube having opposite ends in communication with the headers for fluid flow therethrough, an outer tube closely fitted to the inner tube for the direct flow of heat from one tube to the other, peripheral fin formations carried by the outer tube in the path of fluid flow exteriorly of the tube, and a duct formed in the abutting surfaces of the tubes to provide a drainage canal for fluid leakage from the interior of the inner tube, and a collecting chamber common to the ducts of the several passages.

5. An air cooler including a pair of spaced headers, a series of tubes connecting the headers for the flow of liquid from one to the other, outer tubes exposed to air currents and tightly sleeved on the respective liquid flow tubes, heat absorbing fins carried peripherally on the outer tubes, a drain duct formed in at least one of the abutting surfaces of the tubes to carry off liquid leakage from the inner tube and a collecting chamber common to the drain ducts of the several tubes.

6. In an air cooler of the class described, a pair of spaced headers adapted for connection with a liquid circulating system, a series of liquid flow tubes connecting the headers, a liquid leakage interceptor enclosing each tube and comprising a sleeve affording conveyance for liquid leakage from the tube and having an inside diameter substantially corresponding to the out-

side diameter of the tube for a closely fitted intimate surface contact throughout the entire surface area of the tube except for a passage formed on the inner surface of said sleeve, fins peripherally carried by the sleeve and adapted to be traversed by air currents for the direct transfer of heat through the fins, the sleeve and the tube between the air flowing over the fins and the liquid flowing through the tube, and a liquid leakage collecting chamber common to the several interceptor sleeves.

7. In a motor or generator air cooler, a pair of spaced tanks having inlet and outlet connections for the flow of cooling liquid, a series of heat exchanging tube assemblies joining said tanks and each comprising a pair of nested tubes, with the opposite ends of the inner tube only in communication with said tanks for the transfer of liquid from one to the other and air fins carried by the outer tube to project into the path of air flow for the exchange of heat between liquid flowing through the inner tube and air flowing over the fins, one of said tubes being formed so as to provide a drainage canal between said tubes and a drain collecting header communicating with the ends of the outer tubes of the several assemblies to receive liquid leakage through the inner tube walls and intercepted by the outer tubes.

8. In a cooler of the character described, a pair of headers, a series of heat exchanger conduits, each comprising an inner tube having its opposite ends connected with said headers for fluid flow from one header to the other and a fluid leakage interceptor tube sleeved upon and closely fitted to the inner tube and drain means associated with the several interceptor tubes, said means including a drainage collecting chamber common to all the interceptor tubes.

ALBERT O. FLINDT. 40
